UNITED STATES PATENT OFFICE.

HARRY M. GRIMES, OF KOKOMO, INDIANA.

GAME.

REISSUED

1,285,132.

Specification of Letters Patent. Patented Nov. 19, 1918.

Application filed March 7, 1916. Serial No. 82,555.

To all whom it may concern:

Be it known that I, HARRY M. GRIMES, a citizen of the United States, residing at Kokomo, in the county of Howard and State 5 of Indiana, have invented certain new and useful Improvements in Games, of which the following is a specification.

This invention relates to game boards, and particularly to a game board upon 10 which may be played a game of base-ball.

The primary object of the invention is to provide a board upon which are positioned a number of figures representing the various factors necessary to playing the 15 game of baseball, the arrangement involving means for actuating the various figures to simulate the movements and actions of men players in their respective positions upon an actual ball field, and to carry into 20 effect the various plays common to a real baseball game.

With these objects in view, together with others which will appear as the description proceeds, the invention resides in the novel 25 combination and arrangement of parts all as will be more fully described hereinafter, illustrated in the drawings, and particularly pointed out in the claims.

In the drawings:

30 Fig. 1 is a perspective view of a game board constructed and arranged in accordance with my invention.

Fig. 2 is an enlarged sectional view taken on line 2—2 of Fig. 1.

35 Fig. 3 is a similar view of one of the ball catching devices.

Fig. 4 is a top plan view of the game board, the top being removed, and showing the various movable parts of the device.

40 Fig. 5 is a detail sectional view of the figure representing a batter, showing its operating mechanism.

Fig. 6 is a view taken on line 6—6 of Fig. 5.

45 Fig. 7 is a detail perspective view showing the connection, between the figure and its supporting mechanism.

Fig. 8 is an enlarged sectional view taken on line 8—8 of Fig. 4.

50 Fig. 9 is a fragmentary plan view illustrating the connection between the base-running figures and their cars.

Fig. 10 is a sectional view taken on line 10—10 of Fig. 9.

55 Fig. 11 is a view of one of the figures

representing one of the outfields for the game.

Fig. 12 is a sectional view taken on line 12—12 of Fig. 4, and

Fig. 13 is a plan view of the portion of 60 the device shown in Fig. 12.

Referring to the drawings, 12 indicates the board upon which the playing field is located, the said board comprising upper and lower surfaces or boards 13 and 14 respectively, co-extensive with each other and spaced apart by means of blocks 15 to provide a chamber. Strips 16 project above the upper surface of the board 13 at the edges thereof to prevent the balls used in 70 playing the game from rolling beyond the game board.

The upper board 13 is provided inwardly from its edges with a rectangular or diamond shaped figure, the same being painted 75 thereon to represent the base paths for the field. A slot 17 is provided in the board 13 and is co-extensive with the base paths. A channel 18 is arranged beneath this slot and communicates with the latter at its upper open side. This channel comprises a bottom 18^a and sides 18^b, 18^c respectively; the side 18^b lying relatively close to the innermost edge of the slot 17 throughout the extent of the latter, while the side wall 18^c 85 is arranged beyond the corresponding edge of the slot 17. The purpose of this construction will appear later.

Located beneath the board 13 adjacent one corner of the diamond is a sprocket wheel 90 19, a chain 20 being trained over said sprocket and resting within the channel 18 beneath the slot and being co-extensive therewith. The shaft 21 which supports the sprocket wheel 19 is also equipped with a 95 power sprocket 22, over which passes a power chain 23 adapted to receive power from a sprocket 24, secured upon a shaft 25 remote from the diamond and operated or rotated by means of a detachable handle 26. Upon operation of the handle 26 it is obvious that the chain resting against the wall 18^b of the channel 18 beneath the slot 17 will be driven around the same throughout the extent of the base paths. A car 27 is mounted for sliding movement within the channel 18, and is provided with a vertically disposed shaft 28, to which is secured a sector 29, the teeth of which are adapted to engage in the links of the chain 20. A stop or pin 31 is arranged

on the car 27 in such position as to limit the movement of the sector to 180 degrees in each direction. A game piece 32 indicating a man in the act of running is provided with a stem 33 projecting downwardly from one of his feet to be detachably secured to the shaft 28, and it is apparent the movement of the chain 20 within the channel 18 will, through the car 27, cause the figure 32 to travel 10 around the base paths. The chain and sector arrangement is such that initial movement of the chain will cause the sector and its supporting shaft to rotate 180 degrees, or until the stop 31 is engaged by the outer- 15 most of the teeth 30, and this action causes a similar movement to the figure 33. When the movement of the chain 20 is reversed a similar action takes place, whereby the figure 32 will at all times first face in the direction of movement of the chain before actually traveling with the same. The ends of the car 27 are rounded as at 34 to permit of the same sliding around similar shaped corners in the channel 18 at the juncture of the various base paths.

Located centrally of the diamond shaped figure is the pitcher's box or position. A slot 35 is made in the upper board 13 to extend laterally of the diamond. A rock bar 36 is pivoted at 36' within the chamber between the upper and lower boards of the field to extend at right angles to the slot 35 and beneath the same. A handle 37 is secured at one end of the bar 36 to project through a 35 slot 38 in the board 13 whereby the bar 36 may be rocked. A block 39 is mounted upon the upper surface of the bar 36 beneath the slot 35, and a rock lever 40 is pivoted as at 41 for rocking movement in said block longitudinally of the bar 36 and laterally of the slot 35, being limited in its forward and rearward movements by engagement with the edges of said slot. A figure 41' representing a man in the act of throwing a ball 45 has one of his feet provided with a stem 42 for detachable engagement with the rock lever 40. The outstretched hand of the figure is provided with a cup 43 for the reception of a ball, the said cup being so arranged 50 or tilted as to hold a ball and has its open end facing in the direction of the home base of the field. A contractile spring 44 connects the lever 40 with the forward portion of the bar 36, whereby the former is normally held at the limit of its forward movement. To facilitate retracting the lever 40 against the tension of the spring 44, a trigger member 45 is provided. This member is connected at its forward end to said lever 55 and extends rearwardly therefrom to terminate in a grip member 46 projecting upwardly through a slot 47 formed in the board 13 remote from the pitcher's box or position. In operation, the trigger 45 is re- 60 tracted until the figure is in extreme rear-

ward tilting position. A ball is placed in the cup 43 and the trigger is released, whereupon the spring 44 violently rocks the lever and the figure carried thereby to forward position, and the ball is thrown from the cup 70 in the direction of the home base of the diamond where a batsman is positioned. By oscillating the rock bar 36 lengthwise of the slot 35 it is obvious that the figure 41' will be turned more or less, and such turning will 75 cause the ball to be thrown to either side or across the center of the home base, accordingly as the figure is turned.

A shaft 48 is mounted for rotation in a bar 49 adjacent one corner of the diamond, 80 the said corner being designated the home-base. The bar 49 is in all respects similar to the bar 36 supporting the figure representing the pitcher, being provided with the handle 50 projecting through a slot 51 formed to extend transversely of the board in the rear of the home base. The shaft 48 carries a pulley or drum 52, to the periphery of which is secured one end of a contractile spring 53, the opposite end of the spring 90 being secured to one side of the bar 49 adapted to rock as shown by the dotted line positions in the drawing. Secured to the periphery of the pulley opposite to the point of connection of the spring 53 is one 95 end of a flexible member 54 which may be in the form of a strap which is attached at its opposite end to a trigger rod 55 mounted for sliding movement in suitable keepers 56 on the adjacent side of the bar 49, the said 100 trigger bar terminating in an upwardly extending finger-grip 57 projecting through a slot 58 in the board 13. A block 59 is secured to the upper surface of the rock bar 49, the 105 said block being provided with a central orifice through which a stem 60 secured to a figure 61 extends for connection with the adjacent end of the shaft 48. This shaft is cut away to form a tongue 62 to engage within a socket 63 arranged on the stem end, 110 whereby a connection between the members effected, such as will permit of the ready removal of the figure 61 from the board. The figure represents a batsman in the act of striking at a ball, having a bat 64 in his 115 extended arms. The spring 53 normally holds the pulley in such position that the figure carried thereby is at the extreme limit of striking position, and retraction of the trigger 55 will cause the figure to turn and 120 assume a position ready to strike. Releasing of the trigger allows the spring 53 to rapidly swing the figure to strike at a ball delivered from the pitching figure heretofore described. The rock bar upon which the batsman figure is mounted may be removed accordingly as the pitching figure is inclined. It is also obvious that various slight reciprocating movements of the trigger 55 will cause the figure representing the 125 130

batter to simulate the movements of a batter during an actual game. By permitting the trigger to move only a slight distance forward, the bat held by the figure will be 5 disposed directly over the home plate, whereupon the "bunt" hit common to a base ball game may be actually made.

Mounted for lateral sliding movement in the chamber between the boards 13 and 14, and adjacent the outer end of the field is a frame 65. This frame includes forwardly extending spaced arms 66, and angularly disposed bars 67 connecting the said arms with the base of the frame. Guide blocks 15 68 are secured to the base board 14 to hold the frame 65 in proper sliding position. Figures 69 are secured at various points in the extent of the frame to project through slots 70 in the board 13 of the field. These 20 figures represent the first, second and third basemen, the short stop, and the left, center and right fielders respectively, and are arranged upon the frame according to the true position to be assumed by such players. A 25 handle 71 is attached to the frame 65 to permit the latter to be manipulated. By imparting sliding movement to the frame 65 the figures carried thereby may be shifted to "play" such positions as may be desired. 30 The figures 69 representing the fielders are each equipped with a plate 72 to contact a ball batted by the batsman 61, and pegs 73 may be arranged to project from the feet of the figures to extend through the slots 70 35 into suitable sockets 74 in the frame 65.

Arranged in the outermost walls 18° of the channel 18 at the corners of the diamond representing first, second and third bases are gates 75. These gates are pivoted at one 40 end as at 76 to swing outwardly, rods 77 being connected to each gate at one end and being extended therefrom to a remote corner of the field to present finger grips 78 extending through suitable openings in the board 45 13. There is a similar gate 79 in said channel member slightly to the right of the home plate, the said gate being opened or closed by a knob 80, and a spring 81 holds the said gate normally open. The gates at the various 50 bases are slightly curved as shown, and when the cars carrying the base runners approach, the gates being held closed by the rods 77, the said cars will be permitted to round the corner of the channel and continue on to the next base, but should the control rods be released the cars will crowd against and force the gates outwardly slightly to permit the car being disengaged from the chain 20. The car will remain in 55 this position until the gate is closed to force the same into operative connection with the chain. It is obvious that the various base runner cars may be thus selectively manipulated to halt or advance as desired to properly 60 simulate the activities of a runner in

an actual game. When a batter is "up" or having his turn at bat, a runner figure is positioned upon a car and the latter rests in position at the right of the home plate against the gate 79 and out of contact with 70 the chain 20. When the ball is struck the gate 79 may be forced closed against the tension of spring 81, whereupon the sector on said car comes into operative engagement with the traveling chain and the runner is 75 made to advance to first base.

Each base is equipped with a catching device in the shape of a funnel 82, the same being flared and open at its upper end and being curved and contracted to provide an outlet 80 at its opposite end to deliver the balls to the playing field. It is to be understood that a ball dropped into one of these catchers is to be credited as a "catch" by the respective basemen. Pegs 83 may be secured to project from the under side of the funnels to 85 secure the latter detachably to the playing field. It is thus seen that all of the figures and equipment may be readily removed from the playing field when desired. 90

In order that a ball thrown from the pitching figure to the batting figure which the latter lets go past or fails to hit may be returned to the pitching figure without the aid of the hands of the game operators, a catching device is employed. This device comprises a relatively large cup shaped member 84 secured to the board 13 directly behind the batting figure in such manner that all balls thrown in that direction and which pass 95 the batter will be directed into the same. This catcher may be secured at one edge to a block 85, the latter being secured to the field board by screws 86, whereby the device may be conveniently removed when desired. 100 An opening or slot 87 is made in the board 13 slightly in advance of the home plate, and the immediate upper surface of the said board is slanted or beveled as at 88 to direct balls discharged from the catcher 84 into 110 the opening 87. From the opening 87 the balls are conducted beneath the field board 13 toward the center of the diamond in the inclined groove or channel 89. Mounted for oscillation beneath the board 13 slightly in 115 advance of the pitching figure is a roller 90. This roller may be provided with laterally projecting pintles 91 resting in suitable bearings in supporting blocks 92, the said roller being mounted for oscillation in the direction of the home plate and second base. The periphery of the roller 90 projects into a slot 93 in the surface of the field, and an arm 94 is secured at one end to said roller and normally lies flat upon the board 13 in a forward direction. The forward free end of 120 the arm 94 is equipped with a collector member 95, the latter projecting downwardly through an opening 96 in the board 13 adjacent the forward end of said arm. This 125 130

4
1 collector normally extends at its outer end to the bottom of the inclined way 89, is trough shape in construction, and is provided at its extremity with a ball retaining 5 lip 97. The distance between the collector 95 and its rocking base is equal to that between the ball retaining cup in the pitcher figure's outstretched hand when in "forward" position and the said roller 90, and 10 it is obvious that reverse rocking movement of the roller 90 will cause the arm 94 to move rearwardly and to deliver a ball carried by the member through the rear open end of the latter into the cup held in the 15 pitcher figure's hand. To normally hold the arm in operative horizontal position a spring 98 is employed, the said spring being connected at one end to the roller 90 and at its opposite end to a fixed part of 20 the game board, and it is apparent that this construction yieldably holds the roller and its related parts in forwardly extended or ball receiving position. A strap 99 may be secured at one end to an actuating lever 100 25 projecting through a suitable opening in the face of the board 13 in the rear of the pitcher figure, whereby the roller may be oscillated rearwardly to deliver a ball to the cup held by the pitcher figure.

30 While the above is a description of the preferred embodiment of my invention, it is apparent that various changes may be made in the minor details of construction and arrangement of parts without departing from 35 the spirit of the invention or the scope of the claims.

I claim:

1. In a device of the class described, a board having a transversely disposed slot, 40 a block beneath said board adjacent said slot, a lever on said block adapted to rock transversely of said slot and to project therethrough, means for yieldably holding said lever at the extreme limit of movement in 45 one direction, a game piece on said lever, a cup on said game piece, and a latch for retracting said lever substantially as described.

2. In a device of the class described, a board having a transversely disposed slot, a 50 rock bar mounted beneath said board to oscillate longitudinally of said slot, a block on said bar, a rock lever on said block

adapted to rock transversely of said slot and to project therethrough, means for yieldably holding said lever at the extreme 55 limit of movement in one direction, a game piece on said lever, a cup on said game piece, a latch on said bar and connected to said lever for retracting the latter, and means for rocking said bar substantially as described. 60

3. In a device of the class described, a board having a transversely disposed slot, a rock bar mounted beneath said board to oscillate longitudinally of said slot, a shaft on said bar, a pulley on said shaft, means 65 for yieldably holding said pulley retracted, means for rotating said pulley against the tension of said holding means, and a game piece detachably secured on said shaft to project above said board substantially as described. 70

4. In a device of the class described, a board, means for projecting a ball above and horizontally across said board, a cup having its open end lying in the path of 75 said ball and having its lower end open and communicating with said board, the said board being provided with an opening in advance of said cup, an inclined surface beneath said opening, and means for delivering a ball from said surface to said ball projecting means substantially as described. 80

5. In a device of the class described, a board, a ball delivering means on said board, a ball collecting means, the said latter means 85 comprising a roller, an arm on said roller, a trough on said arm, a spring for holding said arm in forward position, and means for retracting said arm to aline said trough with said ball delivering means, substantially as 90 described.

6. In a device of the class described, in combination, a trackway, means for making figures move in said trackway, a ball delivering device, a ball catching device and 95 means for returning a ball from said catching to said delivering device substantially as described.

In testimony whereof I affix my signature in the presence of two witnesses.

HARRY M. GRIMES.
